CLAIM

The ornamental design for a cover for electronic device, as shown and described.

DESCRIPTION

FIG. 1 is a front perspective view of a cover for electronic device showing our new design;
FIG. 2 is a front view thereof;
FIG. 3 is a rear view thereof;
FIG. 4 is a left-side view thereof;
FIG. 5 is a right-side view thereof;
FIG. 6 is a top view thereof;
FIG. 7 is a bottom view thereof; and,
FIG. 8 is a rear perspective view thereof.

The evenly-dashed broken lines in the figures depict portions of the cover for electronic device that form no part of the claimed design.

The grayscale tones shown in the drawings represent a contrast in appearance.
